(57) **CLAIM**

The ornamental design for a pair of light emitting ornaments for a toy military helicopter, as shown and described.

DESCRIPTION

FIG. 1 is a front perspective view showing my new design for a pair of light emitting ornaments for a toy military helicopter, shown attached by way of struts to the right and left armament booms of a toy military helicopter said environmental structure being shown in broken lines;

FIG. 2 is a right side view of the right side ornament, wherein the right side view of the left side ornament is identical, and the left side views of the right and left side ornaments are symmetrical;

FIG. 3 is a rear view of the left side ornament, wherein the rear view of the right side ornament is identical;

FIG. 4 is a top view of the right side ornament, wherein the right side armament boom has been made transparent so as not to obscure the top of the right side ornament and mounting strut, and wherein the top view of the left side ornament is identical;

FIG. 5 is a bottom view of the right side ornament, wherein the bottom view of the left side ornament is identical;

FIG. 6 is a top right perspective view of the right side ornament, the top left side view of the left side ornament being symmetrical thereto;

FIG. 7 is a top right perspective view showing the design with both ornaments emitting light;

FIG. 8 is a top right perspective view showing the design with the right side ornament emitting light;

FIG. 9 is a top right perspective view showing the design with the left side ornament emitting light; and,

FIG. 10 is a top right perspective view showing the design with neither ornament emitting light.

The broken lines are included for the purpose of illustrating environmental structure that forms no part of the claimed design.
